UNITED STATES PATENT OFFICE

106,691

DESIGN FOR A BOOKEND

William E. Mackelfresh, Jr., Chicago, Ill., assignor to Owens-Illinois Glass Company, Toledo, Ohio, a corporation of Ohio

Application September 22, 1937, Serial No. 71,722

Term of patent 14 years

To all whom it may concern:

Be it known that I, William E. Mackelfresh, Jr., a citizen of the United States, residing at Chicago, in the county of Cook and State of Illinois, have invented a new, original, and ornamental Design for a Bookend of which the following is a specification, reference being had to the accompanying drawing forming a part thereof.

In the drawing:

Fig. 1 is a front elevational view of a bookend showing my new design.

Fig. 2 is a side elevational view thereof.

Fig. 3 is a horizontal sectional view taken on line 3—3 of Fig. 1.

I claim:

The ornamental design for a bookend substantially as shown.

WILLIAM E. MACKELFRESH, JR.
